United States Patent

Des. 238,464
Patented Jan. 20, 1976

238,464

TOILET TISSUE HOLDER

Arthur E. Bauman, 764 Johnston St.,
Akron, Ohio 44306

Filed Nov. 1, 1973, Ser. No. 411,906

Term of patent 14 years

Int. Cl. D23—02

U.S. Cl. D6—97

The sole drawing figure is a perspective view of a toilet tissue holder showing my new design.

I claim:

The ornamental design for a toilet tissue holder, substantially as shown and described.
